PRESSURE-REDUCING VALVE FOR BREATHING APPARATUS

BACKGROUND OF THE INVENTION

The invention relates to a pressure-reducing valve of the first stage for a breathing apparatus provided with a two-stage pressure reducing system, which is able to maintain a constant average pressure independently of the pressure existing in the gas cylinder.

There is known a breathing apparatus in which the compressed air coming from the cylinder is reduced to the breathing pressure by means of two pressure-reducing valves. The first valve reduces the high pressure of the air coming from the air-supply cylinder to the intermediate pressure, which mostly does not exceed 8 atmospheres (atm). The second valve, controlled by the lung of the user reduces this pressure to a breathing pressure. The pressure reducing valves of the first stage of known devices have the essential disadvantage that they do not ensure a constant intermediate pressure, which increases as the pressure in the cylinder drops.

Simplifying the matter somewhat it may be assumed, that the increase of the intermediate pressure depends only on the area of the throttling hole. The higher pressure of the air coming from the cylinder upon the valve head of the pressure-reducing valve effects a more intensive increase of the intermediate pressure. These variations cause varied breathing resistances and disadvantageously influence the breathing characteristic of the device. Use of the throttling hole of small area eliminates these disadvantages to some extent, but causes strong throttling of the flow at high demand of the air.

There are also known pressure-reducing valves which assure maintenance of the constant intermediate pressure, but they are characterized by their complicated and not readily manufactured structure.

SUMMARY OF THE INVENTION

The pressure-reducing valve according to the invention has a simplified structure and permits use of a throttling hole of large cross-sectional area and able to cover any demand on air, and it simultaneously secures the constant intermediate pressure, independently of the pressure in the cylinder.

The task set in order to eliminate said inconveniences is, according to the invention, accomplished in such manner that the force acting unilaterally on the valve head and effecting the increase of the reduced intermediate pressure at decreasing pressure in the cylinder is eliminated. The valve head is relieved by a force arising from the pressure of the air penetrating through a hole made in the valve head into the space closed by the piston, the latter being movable against the valve head and having an area equal to the area of the throttling hole, so that the valve head is in stability.

BRIEF DESCRIPTION OF THE DRAWING

The pressure-reducing valve is more thoroughly explained by means of an exemplary embodiment in the accompanying drawing, the sole FIGURE of which is a longitudinal sectional view of the valve.

DESCRIPTION OF THE PREFERRED EMBODIMENT

The pressure-reducing valve consists of a valve body 1, a nut fastening the valve to the cylinder 3, a seat 4 with the throttling hole, a chamber of the valve head 6 connected with a piston rod 6 and a piston 11, a spring 10 opening the valve, a cover 12 of the body, a piston 16, and seals 15, 17 and 19 closing the spaces 13, 21 and a chamber 5. In the cover 12 there are made ports 8 leading the environmental (ambient) pressure to the space 9. In this design, instead of the piston 11, a membrane may be applied, connected with the piston rod 7 and the cover 12.

The described design may be used for breathing apparatus

destined for moving under water, as well as for apparatus insulating the human breathing system from gases of the environment.

The mode of operation of the valve according to the invention is as follows:

Before supplying the compressed air from the cylinder, the pressure of the spring 10 upon the piston 11 holds the valve head 6 open. After influx, the air flows from the cylinder through the conduit 2 and the chamber 5 to the conduit 20, 10 which leads the air to the breathing apparatus. The air penetrates also through the hole 18 and the slot 14 to the space 13 above the piston 11. As the suitable value of the reduced pressure is achieved, the pressure of the air upon the piston 11 overcomes the resistance of the spring 10, causes a shifting of the piston, and closes the seat 4. Simultaneously through the hole 22 the air flows to the space 21 closed by the piston 16 abutting against the cover 12 of the valve body, creating thereby the fixed position of the piston 16 in relation to the valve seat 4.

I claim:

1. In a breathing apparatus comprising a compressed-air tank, a first valve connected to said tank for producing air at a constant intermediate pressure less than that in said cylinder, a second valve connected to said first valve for converting air 25 at said intermediate pressure into air at breathing pressure, and a breathing device connected to said second valve for supplying said air to the user, the improvement wherein said first valve includes:

a valve body formed with an inlet connectable with said cylinder with a passage connected to said inlet, with a valve chamber communicating with said passage, and an outlet connected with said second valve;

means in said valve chamber forming a valve seat around said passage;

piston means axially displaceable in said body and including a valve member engageable with said seat and movable toward and away from said seat for blocking and unblocking communication between said passage and said valve chamber, said piston means defining within said body a first compartment expandable with movement of said valve member away from said seat and communicating with the ambient environment, and a second compartment expandable with movement of said valve member toward said seat, said valve member being provided with a port communicating with said passage in a blocking position of said valve member and with a bore extending in the direction of displacement of said valve member and communicating with said port;

a plunger received in said bore and defining therein a piston chamber expanding and contracting with movement of said valve member toward and away from said seat, respectively, and communicating with said valve chamber via said port in an unblocking position of said valve member and communicating with said cylinder via said port in a blocking position of said valve member, said valve member being formed with a further passage connecting said valve member with said second compartment in all positions of said valve member; and

a spring bearing upon said piston means and yieldably resisting contraction of said first compartment.

2. The improvement defined in claim 1 wherein said valve body is provided with a cap defining said compartments with said piston means, said plunger bearing against said cap, said piston means having a piston sealingly and slidably engaging said cap, further seal means between said valve member and said valve body and between said plunger and said valve member, said plunger being formed in said piston chamber of said valve means with an effective surface area equal to that of the valve seat.
